UNITED STATES PATENT OFFICE.

JAMES E. PLEW, OF CHICAGO, ILLINOIS.

BUBBLING DRINKING FOUNTAIN.

Application filed April 18, 1921. Serial No. 462,148.

To all whom it may concern:

Be it known that I, JAMES E. PLEW, a citizen of the United States, residing at Chicago, county of Cook, State of Illinois, have invented a certain new and useful Improvement in Bubbling Drinking Fountains, and declare the following to be a full, clear, and exact description of the same, such as will enable others skilled in the art to which it pertains to make and use the same, reference being had to the accompanying drawings, which form a part of this specification.

One of the difficulties experienced with bubbling drinking fountains attached to ordinary service pipes is that the height of the jet or bubble varies with the pressure in the pipe and, where there is a manual valve between the fountain and the source of supply, the height of the bubble or jet varies according to the position of the valve and, if the valve is opened a little too far, the bubble is transformed into a stream of high velocity. It has heretofore been proposed to overcome this objection by providing reducing valves of one kind or another to control the pressure. My invention has for its object to produce a simpler and more effective means than a reducing valve for preventing the bubble or gentle jet from becoming a violent jet when the pressure at the inlet to the fountain rises.

In carrying out my invention I employ in the fountain a large valve-controlled vent which opens at a predetermined pressure and permits the escape of the water. I have found by making the vent large enough it will take care of the entire flow of water, when once opened, eliminating the bubble. In one of its aspects, my invention may therefore be regarded as having for its object to produce a device which, up to a certain pressure, as when the valve in a faucet is only partly opened, will serve as a bubbling drinking fountain while, at higher pressure, as where the valve in a faucet is opened wide, it will serve simply as an ordinary discharge outlet for a faucet or pipe.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 illustrates a basin provided with a faucet having attached thereto one of my improved devices; and

Fig. 2 is a vertical section through the fountain device, on a larger scale than Fig. 1.

For the sake of brevity I have illustrated in the drawing and shall describe with particularity only a single embodiment of my invention in a shape adapted to be attached to a faucet or supply pipe; but I desire to have it understood that my invention may take various other forms and be capable of being supplied with water in various other ways.

Referring to the drawing, 1 represents a bell-shaped member having at the axis a downwardly-projecting tubular member, 2, opening out of the top of the bell. Water is delivered into the interior of the member 1 through a supply pipe, 3. The lower end of the bell is closed by a disc, 4, which is yieldingly held up against a downwardly-facing annular shoulder, 5, at the base of an apron or flange, 6, forming the bottom of the bell and of somewhat larger diameter than the remainder. A post, 7, extends down from the tube 2 through the center of the disc and, resting on a nut, 8, on the lower end of the post is a spring, 9, which at its upper end supports the disc. The upper end of the spring passes through a small hole, 10, in the disc and is thereby prevented from turning. The extreme lower end, 11, of the spring is bent so as to lie parallel with the axis of the post and just beside the nut 8, thus serving as a nut lock.

Assuming that the member 3 is the discharge side of a faucet, 12, associated with a basin, 14, above which the fountain device lies, the operation is as follows: When the water is turned on by reason of the faucet being partially opened, it flows into the interior of the bell-shaped member and rises until it reaches the bottom of the tube 2. The water then flows up through the tube and forms a bubble or gentle jet at the top. As the water rises within the bell on the outside of the tube, the air trapped within the upper end of the bell is compressed and it thereafter serves as a pressure-equalizing device which will take care of small variations in pressure. In case the pressure for any reason is increased so that ordinarily the flow of water at the drinking point would be more active or violent than is

desirable, the disc, 4, will yield downwardly and permit the water to escape past the same. The pressure at which the disc will yield is controlled by the spring whose tension is in turn controlled by the nut on the lower end of the post.

I have found that by making the vent opening of a large size, preferably larger than the area of the supply pipe, the discharge of water through the vent, having once been begun, will rob the drinking point of its supply so that the entire flow will be out through the vent. This is true no matter whether the vent is at the side or at the bottom and it is also true with the device as illustrated if it be turned completely upside-down. The result is that no matter where the vent is located in the fountain, it may be made to serve as the sole active discharge outlet so that water may be drawn from the faucet or other supply device into a pail or other receptacle just as though the fountain attachment were not present. In other words, whenever it is desired to use the device as a bubbling drinking fountain and the conditions are proper for comfortable and convenient drinking, the device will act as a bubbling drinking fountain and when the improper condition of high pressure exists, the person desiring to drink is protected against a violent discharge of water and can regulate the flow from the manual valve, and when it is desired simply to draw from the faucet or other supply device a large quantity of water, the fountain device no longer acts as a bubbling fountain but simply as a discharge outlet of sufficient capacity to deliver all of the water which reaches it. The depending flange, 6, directs the flow of the water passing out through the vent and keeps it from being discharged sidewise and wetting those in the vicinity thereof. Furthermore, when the water is being drawn off rapidly for the purpose of filling a pail or other receptacle, the discharge has the appearance of a large solid stream.

It will thus be seen that the member 1, no matter what form or shape it may take, is intended to serve as a chamber for receiving water and delivering it through a drinking outlet or through a vent outlet, the latter preferably of large capacity; the receiving chamber also preferably trapping a certain amount of air for regulating purposes. It will also be seen that the spring supported disc, 4, is simply representative of that class of devices, no matter where placed with respect to the water-receiving chamber or of what shape or of the means by which it is yieldingly held, which may serve as an inwardly-closing check valve, pressure on which is obtained in any suitable way and the pressure of which may be regulated in any suitable way.

As heretofore explained, my invention is not limited to the details of the specific device illustrated and described with particularity, as my invention may take any one of a great variety of forms and I intend to cover all forms and arrangements which come within the terms of the definitions of my invention constituting the appended claims.

I claim:

1. In a device of the character described, a receiving chamber having an inlet and two outlets, one of the outlets being a constantly-opening drinking outlet, and an inwardly-closing check valve controlling the other outlet. 75
2. In a device of the character described, a receiving chamber having an inlet and a plurality of outlets, one of the outlets being a constantly-open drinking outlet, and inwardly-closing check valve means controlling the remainder of the outlets. 80
3. In a device of the character described, a receiving chamber having an inlet and a constantly-open drinking outlet, a second outlet of larger cross sectional area than the drinking outlet, and means for holding the second outlet closed until predetermined pressure is reached in the chamber. 85
4. In a device of the character described, a device having an inlet opening and a drinking outlet opening, said chamber having also a second outlet opening of a cross sectional area greater than that of the inlet opening, and means under the control of pressure within the chamber for closing said second outlet. 90
5. In a device of the character described, a receiving chamber having an inlet opening and two outlet openings, one of the outlet openings being constantly open and affording a drinking point, an inwardly-closing check valve controlling the other outlet opening, and means for varying the pressure which tends to hold the valve seated. 105
6. In a device of the character described, a receiving chamber, a supply conduit connected to said chamber, an unobstructed tube arranged within the chamber and opening out of the same to afford a drinking point, the inlet end of the tube being at a considerable distance from the wall of the chamber through which the tube passes and being also out of the path of the stream issuing into the chamber from the supply conduit, said chamber having an additional discharge outlet, and means under the control of the pressure in the chamber for controlling the said outlet. 115
7. In a device of the character described, a receiving chamber open at the bottom and having a small drinking outlet at the top, a cover for the bottom of the chamber in the form of an outwardly-opening check valve adapted to open and close the bottom of the chamber, the lower end of the walls of the 120
- 125
- 130
- 135
- 140

chamber being continued down past the cover to form a deflector for water passing out of the chamber around the cover, said chamber having also a water inlet.

- 5 8. In a device of the character described, a bell-shaped member having a drinking outlet at the top, an upwardly-seating valve for closing the lower end of the bell lying in the bell at some distance above the lower edge
- 10 of the latter, means for yieldingly holding the valve seated, the parts being so proportioned that the valve when open does not pass beyond the lower edge of the bell, and means for admitting water into the interior
- 15 of the bell.
- 9. In a device of the character described, a bell-shaped member having a drinking outlet at the top, a tube extending downwardly into the bell from the drinking outlet, an
- 20 upwardly-seating valve for closing the lower end of the bell lying in the bell at some distance above the lower edge of the latter, means for yieldingly holding the valve seated, the parts being so proportioned that the
- 25 valve when open does not pass beyond the lower edge of the bell, and means for admitting water into the interior of the bell in such a manner that the incoming stream is not in line with the passage through the
- 30 tube.

10. In a device of the character described, a bell-shaped member having at the axis a downwardly-projecting tubular post forming at its upper end a drinking outlet, an

- 35 upwardly-seating valve mounted on the lower end of said post for closing the lower end of said member, and said member having an inlet.

11. In a device of the character described,

- 40 a bell-shaped member having a drinking outlet at the top and a water inlet at a point below the top, and an upwardly-seating valve forming a closure for the mouth of the bell-shaped member.

12. In a device of the character described, 45 a receiving chamber having an inlet and a constantly-open drinking outlet, and means for providing an additional outlet from said chamber when the pressure in the chamber rises above a predetermined point and for 50 again closing the additional outlet when the pressure in the chamber drops below said predetermined point.

13. In a device of the character described, a device having an inlet opening and a constantly-open drinking outlet opening, said chamber having a second outlet opening of 55 a cross sectional area greater than that of the inlet opening, and means under control of the pressure within the chamber for 60 closing said second outlet opening.

14. In a device of the character described, a receiving chamber open at the bottom and having at the top a drinking outlet much smaller in cross sectional area than the open 65 bottom, a cover for the bottom of the chamber, and the chamber and the cover being movable relatively to each other to open the bottom of the chamber when the pressure in the chamber rises above a predetermined 70 point, said chamber having also a water inlet.

15. In a device of the character described, a receiving chamber open at the bottom and having at the top a drinking outlet much 75 smaller in cross sectional area than the open bottom, a cover for the bottom of the chamber, and the chamber and the cover being movable relatively to each other to open the bottom of the chamber when the pressure in 80 the chamber rises above a predetermined point, the lower end of the walls of the chamber being continued down past the cover to form a deflector for water passing out of the chamber around the cover. 85

In testimony whereof, I sign this specification.

JAMES E. PLEW.
